UNITED STATES PATENT OFFICE.

ALBERT E. TABER, OF GREATFALLS, MONTANA.

FEED-WATER HEATER.

SPECIFICATION forming part of Letters Patent No. 729,907, dated June 2, 1903.

Application filed June 3, 1902. Serial No. 110,067. (No model.)

To all whom it may concern:

Be it known that I, ALBERT E. TABER, a citizen of the United States, residing at Greatfalls, in the county of Cascade and State of Montana, have invented new and useful Improvements in Feed-Water Heaters, of which the following is a specification.

My invention relates to improvements in feed-water heaters; and its novelty, utility, and practical advantages will be fully understood from the following description and claims when taken in conjunction with the accompanying drawings, in which—

Figure 1 is an elevation, partly in section, of the left side of so much of a locomotive-boiler as is necessary to illustrate my invention; Fig. 2, a similar view of the right side of the boiler; Fig. 3, a transverse section taken in the plane indicated by the broken line 3 3 of Fig. 1; Fig. 4, an enlarged detail section illustrating the arrangement of the pipes for supporting and supplying my improved combined water-box and baffle in the fire-box of the boiler; Fig. 5, an elevation of the combined water-box and baffle which I prefer to employ; Fig. 6, an end elevation of the same; Fig. 7, a vertical transverse section taken in the plane indicated by the broken line 7 7 of Fig. 5, and Fig. 8 a horizontal transverse section taken in the plane indicated by the broken line 8 8 of Fig. 5.

Referring by letter to the said drawings, and more particularly to Figs. 1 to 4 thereof, A is a locomotive-boiler having the usual fire-box *a* and water-leg *b*, and B is the combined water-box and baffle of my improvements. This box B, which is constructed of steel, in such manner as to enable it to withstand great pressure, is disposed in the fire-box at about the angle of inclination shown in Fig. 1, so as to adapt it to serve the purpose of the ordinary baffle-plate and at the same time present it to the direct action of the fire. It is supported in position by pipes or rods C and pipes D D', which are screwed into its ends and extend through transverse sleeves *c*, fixed in the walls of the water-legs, and is also supported by pipes E, which connect its upper portion with the water-space of the boiler. From the bottom of said water-box

I prefer to extend a pipe *d*, equipped with a blow-off *e*, as illustrated.

F is an injector arranged to be supplied with steam from the boiler and with water from the locomotive-tender or any other source of supply; *G*, a pipe connecting the injector and the pipe *D* and provided with a check or non-return valve *H*, arranged to seat in a direction away from the water-box *B*; *I*, a pipe connecting the pipe *D* and the lower portion of the water-leg *b* and also having a check or non-return valve *H'*, arranged to seat in a direction away from the box *B*, and *K* a pipe disposed, by preference, at the left side of the boiler and between the pipe *D'* and the upper portion of the water-space of the boiler and provided with a check or non-return valve *H*², arranged, like the valves *H* *H'*, to seat in a direction away from the box *B*.

In practice when steam is let into the injector *F* and the same is operating to force water past valve *H* and through pipe *G*, pipe *D*, water-box *B*, and pipes *E* into the boiler the valves *H'* *H*² are held against their seats and communication between the box *B* and the boiler through pipes *I* and *K* is closed. When, however, steam is cut off from the injector and the same ceases to force feed-water to be heated through the box *B*, the valve *H* seats and closes communication between the boiler and the injector, while the valves *H'* *H*² open under the weight of the water and permit the water to circulate from the lower and upper portions of the boiler through pipes *I* and *K*, pipes *D* *D'*, the water-box *B*, and pipes *E* back into the boiler. This circulation of the water through the box *B* while the injector is idle not only assists in making steam, but precludes burning out of the box *B*.

It will be appreciated from the foregoing that by virtue of my improvements the feed-water is thoroughly heated precedent to entering the boiler, and while the injector is idle a circulation of water through the boiler and box *B* is maintained, as is desirable.

While I prefer to employ the pipes *D'* and *K* and the valve *H*², I do not desire to be understood as limiting myself to the same, as they may be omitted without destroying the operativeness of my improvements. In the

event of the pipe D' being dispensed with a plugged pipe or rod, such as C, will be employed to assist in supporting and holding the box B in position.

- 5 The combined water-box and baffle of my improvements may be of the construction shown in Figs. 1 and 4 and indicated by B or of any other construction calculated to withstand great pressure without departure 10 from the scope of my invention. I prefer, however, to have the combined water-box and baffle embody the construction shown in Figs. 5 to 8 and indicated by B'. This latter construction, Figs. 5 to 8, comprises a flat 15 plate m, of steel, which forms a portion of the uppermost side wall of the box and baffle; a steel plate n, which forms the lowermost side wall of the box and is bent, as indicated by p and r, to form the bottom and top walls, 20 respectively, of the box and is provided in said bottom and top walls with apertures s t and also in the wall p by preference with a washout-aperture u, normally closed by a plug v; interiorly-threaded pipe-sockets s' t', 25 which surround the apertures s t, respectively, and have flanges connected by rivets to the walls p and r; steel plates w, which form the end walls of the box and have flanges x, arranged at the inner sides of and connected by 30 rivets to the walls m, n, p, and r, and also have apertures y and reinforcing-plates y', connected by rivets to their inner sides and provided with threaded apertures y'', coincident with the apertures y; rivets z, which connect the lapped edges of the plates m n, and transverse stay-bolts a', which are interposed 35 between and connect the upper and lower sides of the box. The pipe-socket s' is designed for the connection of the pipe d, Figs. 40 1 to 3, the pipe-sockets t' for the connection of the pipes E, and the threaded apertures y'' in the reinforcing-plates y' for the connection of the supports and pipes C, D, and D'.

It will be appreciated from the foregoing 45 that by reason of the construction of the combined water-box and baffle B a continuous plate n, free from seams, is presented to the direct action of the fire, which contributes materially to the durability of the box and baffle; 50 also, that the combined water-box and baffle B' as a whole is exceedingly strong, and hence calculated to withstand for a long period the great pressure to which such devices are ordinarily subjected.

55 I have entered into a detailed description of the construction and relative arrangement of parts embraced in the present and preferred embodiment of my invention in order to impart a full, clear, and exact understanding 60 of the same. I do not desire, however, to be understood as confining myself to such specific construction and arrangement of parts, as such changes or modifications may be made in practice as fairly fall within the scope of 65 my claims.

Having described my invention, what I claim, and desire to secure by Letters Patent, is—

1. The combination of a boiler, a water-box disposed in the fire-box of the boiler, one or 70 more pipes connecting the water-box and the water-space of the boiler, a pipe intermediate of the upper portion of the water-space of the boiler and the water-box provided with a check or non-return valve arranged to seat 75 in a direction away from the water-box, a pipe intermediate of the lower portion of the water-space of the boiler and the water-box provided with a check or non-return valve arranged to seat in a direction away from the 80 water-box, an injector, and a pipe intermediate of the injector and the water-box provided with a check or non-return valve arranged to seat in a direction away from the 85 water-box.

2. The combination of a boiler, a water-box disposed in the fire-box of the boiler, one or more pipes connecting the water-box and the water-space of the boiler, an injector, conduits connecting the upper and lower portions 90 of the water-space of the boiler, and the injector with the water-box, and means whereby, when the injector is working, communication between the upper and lower portions of the water-space of the boiler and the water- 95 box through said conduits is cut off, and, when the injector is idle, communication between the water-box and the injector is cut off, and communication between the upper and lower portions of the water-space of the 100 boiler and the water-box is re-established.

3. The combination of a boiler having transverse sleeves secured in the walls of its water-leg, the combined water-box and baffle arranged in an inclined position in the fire- 105 box of the boiler, pipes connecting the upper portion of said water-box and the water-space of the boiler, rods connected to the ends of the water-box and disposed in the upper transverse sleeves, pipes disposed in the lower 110 transverse sleeves and effecting communication between the water-space of the boiler and the lower portion of the water-box, and having check or non-return valves arranged 115 to seat in a direction away from the water-box, an injector, and a pipe leading from one of said pipes at a point between the valve thereof and the water-box to the injector, and having a check or non-return valve arranged to seat in a direction away from the water-box. 120

4. The water-box described for use in a feed-water heater, made up of the plate m forming a portion of one side of the box, the plate n forming the other side and the top and bottom of the box, and having apertures in said 125 top and bottom portions, and also having its edges lapped with and connected to the edges of the plate m, interiorly-threaded pipe-sockets arranged coincident with said apertures of the plate n and having flanges connected 130

thereto, plates forming the ends of the box and having flanges arranged at the inner sides of and connected to the plates *m* and *n*, and also having apertures, and reinforcing-plates provided with coincident threaded apertures, and transverse stay-bolts interposed between and connecting the sides of the box.

In testimony whereof I have hereunto set my hand in presence of two subscribing witnesses.

ALBERT E. TABER.
